UNITED STATES PATENT OFFICE.

THOMAS M. PRICE, OF RALEIGH, NORTH CAROLINA.

STRAINER BOX FOR LOCOMOTIVES.

Application filed September 21, 1923. Serial No. 664,044.

To all whom it may concern:

Be it known that I, THOMAS M. PRICE, a citizen of the United States, residing at Raleigh, in the county of Wake and State 5 of North Carolina, have invented certain new and useful Improvements in Strainer Boxes for Locomotives, of which the following is a full, clear, and exact description.

In taking water into the locomotive tender or tank from the usual penstock or tank found along railroads, it frequently happens that leaves and other rubbish find their way into the locomotive tender. It is therefore usual to provide each locomotive with a 10 strainer box which is placed in the feed water line so as to prevent this foreign matter from reaching the boiler. These strainers often become clogged and prevent the injectors from properly feeding the 15 water to the boilers. Under such circumstances it is necessary to stop the engine, remove the cover of the strainer box and manually remove the collected rubbish therefrom. And again, it sometimes happens 20 that the hose leading from the locomotive tank to the strainer box will become clogged, so as to prevent the free passage of water to the boiler, thereby necessitating a removal of the hose so as to clear the 25 same.

It is an object of the present invention to overcome the foregoing difficulties by providing simple and inexpensive means by which the engineer may clear leaves and 30 other rubbish from the strainer, strainer box or hose without leaving his seat or stopping the engine.

A further object of the invention resides in the provision of means to prevent steam 40 and hot water being driven back into the locomotive tank should there be a leaky check valve in the boiler.

Other objects and advantages of the invention will be apparent from the following 45 description when taken in connection with the accompanying drawings, in which,

Figure 1 is a side elevation of the strainer box and related parts.

Figure 2 is a view similar to that shown 50 in Figure 1 but taken at an angle of 90° thereto.

Figure 3 is a vertical section through the apparatus, and,

Figure 4 is a horizontal section through 55 the latch mechanism.

Referring to the drawings more in detail

the numeral 1 refers to a strainer box provided with the strainer 2 of wire mesh or the like, and a removable cover 3. This box is provided with a pair of couplings or conduits 4 and 5, one being formed on each side thereof. The coupling 4 is adapted to receive one end of the hose leading to the locomotive tank or tender while the coupling 5 is attached to the pipe leading to the boiler injectors. Inasmuch as the boiler injectors and water tank per se form no part of the present invention it has not been deemed necessary to illustrate them on the drawings.

Integrally formed in the strainer box 1 is 70 a slide valve passage 6 which terminates in a valve seat 7 in alignment with the coupling 4. Located in the passageway 6 and adapted for sliding movement therein is a substantially circular valve 8. This valve may 75 assume any one of three positions, namely, that shown in full and dotted lines in Figure 3, or it may be lowered to its seat 7. When seated the valve 8 will, of course, close the passage through the coupling 4; in the 80 first-mentioned positions of the valve 8 however this passage will remain open.

The strainer box 1 is also provided with an exit passage 9 in vertical alignment with the valve 8 and located at the bottom of the 85 box. A valve 10 cooperates with the passageway 9 and is provided with a stem 11 which is surrounded by a coil spring 12, the stem being slidably mounted in a crosshead 13 against which one end of the spring 12 90 engages. Arms 14-14 extend laterally from the crosshead 13 and have the upwardly extending rods 15 secured to the outer ends thereof. These rods are secured at their upper ends to the laterally extending arms 16 of the valve stem 17 of the valve 8. By thus connecting the two valves 10 and 8 it will be seen that they are caused 95 to move in unison.

A rod 18 is pivotally connected to the 100 valve stem 17 as indicated at 19. This rod extends through a fixed portion 20 of the locomotive and has its handle 21 preferably located adjacent the engineer's seat. A plurality of notches 22 are formed in one edge 105 of the rod 18 and provide shoulders adapted to be engaged by a spring-pressed plunger 23 mounted in the casing 24 attached to the fixed portion of the locomotive.

In the operation of the device, if it is desired to clean out the tank hose or the lower portion of the strainer box, the latch 23 is

withdrawn and the rod 17 lowered until the valve 8 assumes its middle position as indicated by dotted lines in Figure 3. This movement of valve 8 will, through the medium of the connecting rods 15, open the valve 10 and permit water to escape from the engine tender through the hose and strainer box to the atmosphere. The escaping water will of course carry with it any leaves or other rubbish collected in these parts of the apparatus. Should it be desired to thoroughly clear the screen or strainer 2, the valve 8 is lowered to its seat 7 thereby sealing the passage through the coupling 4 and opening still farther the valve 10. Steam is now caused to pass from the boiler through the coupling 5 and screen 2 to the atmosphere.

Should one of the boiler check valves start leaking and thereby permit steam and hot water to escape through the strainer box to the locomotive tender it is only necessary to lower the valve 8 to its seat thereby cutting off the backward passage of the steam and permitting the same to escape to the atmosphere.

From the foregoing description it will be seen that I have provided an exceedingly simple construction whereby the strainer, strainer box, and coupling hose may readily be freed from leaves and other rubbish without stopping the engine and without necessitating the engineer to withdraw his attention from the operation of the train.

In accordance with the patent statutes, I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. In a device of the class described, a strainer box having three passages therein leading to the atmosphere, the water tank

and the boiler, said two last-named passages being in substantial alignment, a flat strainer extending across the interior of said box and crossing the axis of said aligned passages, a valve in each of the passages to the tank and to the atmosphere, and means rigidly connecting said valves, whereby the tank passage may be closed when the atmosphere passage is open.

2. In a device of the class described, a strainer box having three passages therein leading to the atmosphere, the water tank and the boiler, said two last-named passages being in substantial alignment, a flat strainer extending across the interior of said box and crossing the axis of said aligned passages, a valve in each of the passages to the tank and to the atmosphere, said valves being constructed and arranged to permit water to flow from the water tank to the atmosphere in one position of the valves and to permit steam to flow from the boiler to the atmosphere in another position of the valves, the latter position of the valves preventing steam from flowing to the water tank.

3. In a device of the class described, a strainer box, a strainer therein, couplings on said box for the tank hose and for the feed pipe to the injectors, said box being provided with an exit passage in the bottom thereof, a spring-pressed valve for said exit passage, a slide valve adjacent said tank coupling and in alignment with said spring-pressed valve, and a pair of rods rigidly connecting said valves.

4. In a device of the class described, a strainer box, a strainer therein, couplings on said box for the tank hose and for the feed pipe to the injectors, said box being provided with an exit passage at the bottom thereof, a spring-pressed valve for said exit passage, a slide valve adjacent said tank coupling and in alignment with said spring-pressed valve, means rigidly connecting said valves, and a latch for holding said valves in adjusted positions.

T. M. PRICE.
